UNITED STATES PATENT OFFICE.

MATILDA R. STEPHENSON, OF CRIPPLE CREEK, COLORADO.

DESIGN FOR A SHOVEL.

SPECIFICATION forming part of Design No. 31,094, dated June 27, 1899.

Application filed June 1, 1899. Serial No. 719,040. Term of patent 7 years.

To all whom it may concern:

Be it known that I, MATILDA R. STEPHENSON, a citizen of the United States, residing at Cripple Creek, in the county of Teller and State of Colorado, have invented and produced a certain new and original Design for Shovels; and I do declare the following to be a full, clear, and exact description of the invention, such as will enable others skilled in the art to 10 which it appertains to make and use the same.

The invention relates to a new and original design for shovels; and it consists of a design of the configuration shown in the accompanying drawing, in which I have illustrated my 15 invention in perspective.

The leading feature of the design comprises the body portion 1, the edges of which are

curved, as shown at 2, and are provided with a V-shaped point 3. Projecting upwardly from the edges is a flange 4, a portion of which is straight, while the other portion is provided with scallops 5.

6 denotes the handle, projecting rearwardly from the upper edge of the scalloped portion.

What I claim is—

The design for a shovel as herein shown and described.

In testimony whereof I have hereunto set my hand in presence of two subscribing witnesses.

MATILDA R. STEPHENSON.
